UNITED STATES PATENT OFFICE.

JOSHUA POOL AND JOSEPH POOL, OF GREENSBURG, INDIANA.

DESIGN FOR MONUMENTS.

Specification forming part of Design No. **11,469**, dated October 21, 1879; application filed September 27, 1879.
[Term of patent 7 years.]

To all whom it may concern:

Be it known that we, JOSHUA POOL and JOSEPH POOL, of Greensburg, in the county of Decatur and State of Indiana, have originated and designed a new Monument, of which the following is a full, clear, and exact description, reference being had to the accompanying drawing, making part of this specification.

The nature of our design is fully represented in the accompanying drawing; and it consists of a monument having a square base, A, made in one or more pieces, on which is mounted our new design of monument, the first section being a base, B, which is square, having its top finished with four gables, B', formed of straight lines with slanting roofs, and a square center, B², tapering from the outer surface of the base B to the base of the die C, and forming a fit with said die. The die C is square, and rests on the base B. The cap D is square-finished, to fit the die C, on which it rests, with a molding formed of a scotia, fillet, and chamfer or bevel. The upper part of the cap D is finished with four gables, D', one on each side, formed of straight lines with slanting roofs or tops, and a square center, D², tapering from the outer edges of the square part of the cap to the base of the shaft E, and forming a fit with said shaft. The shaft E is square, and has a projecting gable, E', on every side at its base, the gables being formed with straight lines, as in the cap D and base B. The shaft also has a projecting gable on each side near its top, the gables corresponding in shape with those at its base, with drops on the corners of the shaft below the gables, as shown.

What we claim as new, and desire to secure by Letters Patent, is—

1. The design of a sectional monument, as shown, to be mounted on the square base A, consisting of a square base, B, with slanting-topped gables B' on its four sides, and a square center, B², tapering from the outer edge of the base to the die C, the square die C, above which is fitted the square cap D, having four slanting-topped gables, D', one on each side, and a square center, D², tapering from the outer edges of the cap to the base of the square shaft E, and the square shaft E, finished at its base and top, all substantially as shown and described.

2. The design of a monument with its various sections fitted together, the base B, the die C, the cap D, and the shaft E, each, except the die C, being provided with slanting-topped gables, and the base B and cap D having square centers, tapering from the outer edges of the said base and cap to fit the sections above each of them, substantially as shown and described.

3. The design as a whole, and each section separately except the die, and each part of each section, substantially as shown and described.

In testimony whereof we have signed our names to this specification in the presence of two subscribing witnesses.

JOSHUA POOL.
JOSEPH POOL.
